UNITED STATES PATENT OFFICE.

GRANT NEWLAND, OF FORT DODGE, IOWA, ASSIGNOR OF ONE-HALF TO JOHN P. WALROD, OF MOORLAND, IOWA.

GATE.

Application filed March 9, 1923. Serial No. 623,916.

To all whom it may concern:

Be it known that I, GRANT NEWLAND, a citizen of the United States, residing at Fort Dodge, in the county of Webster and 5 State of Iowa, have invented certain new and useful Improvements in a Gate, of which the following is a specification.

This invention relates to improvements in gates, and has for its prime object to produce a swinging gate, on which the end farthest from the hinges is supported independently from the latter, thus making the construction of very long gates, as at railroad crossings, practical without the use of 10 heavy structures, massive hinges, braces, or strong posts, and combining economy, lightness, neatness of appearance, and better protection from the ordinary beam-gate.

Another object of the invention is to 20 provide a gate of the character indicated, which is supported at one end by a hinged bracket, so that upon disconnecting the gate from its lower hinge, the gate can be swung to either the right or left and allowed to 25 travel lengthwise of the fence. This is a very desirable feature of the invention in the winter time when the snow is banked up against same and it is impossible to swing the gate all the way around on its hinges.

30 A further object of my invention is to provide a swinging gate that will open to either side and one that will not sag in the center.

A still further object of my invention is to provide a gate, wherein, the supporting 35 members at the opposite end of the gate will act as a stop to hold the gate in an operative position when closed, thus preventing cattle when used as a farm gate from pressing against the gate and accidentally opening the same.

40 And a still further object of my invention is to provide a gate of the above described character which is constructed of piping and one that is durable, simple in construction, and efficient for all purposes intended.

These and like objects of the invention will be better understood as the description proceeds and as is specifically pointed out in the appended claim.

50 Referring to the accompanying drawings which form a part of this specification and which clearly illustrate the construction and operation of my improved gate,

55 Figure 1 represents an elevation of a gate embodying my invention,

Figure 2 is a top plan view of same.

Figure 3 is an enlarged fragmentary side elevation of a section of my improved gate.

Figure 4 is a vertical section taken on line 4-4 of Figure 3.

Figure 5 is a horizontal section taken on line 5-5 of Figure 3.

Figure 6 is a section taken on line 6-6 of Figure 1, and

Figure 7 is a horizontal section taken on line 7-7 of Figure 1.

Referring to the accompanying drawings in detail, like characters will be used to designate like parts in the different views.

In the drawings, the numeral 1 designates the supporting post, having oppositely disposed supporting brackets 2 on which the gate designated as a whole by the numeral 3 is hingedly supported. The gate 3 is constructed of a series of horizontal pipes 4, 75 which are connected at one end adjacent the supporting post 1 by means of a vertical pipe 5 and couplings 6. The opposite end of the upper horizontal pipe 4 is connected to a vertical pipe 7 through a coupling member 8. The middle and lower horizontal pipes 4 are connected at their free ends by means of a vertical pipe 9 and couplings 10. The middle horizontal pipe 4 is connected with the coupling 8 by means of a 85 T-coupling 11, thus forming the frame of my improved gate.

A U-shaped band 12 is secured to the vertical pipe 5 adjacent the lower end of same by means of a pin 13. A bracket receiving 90 chamber 14 is provided in the U-shaped band 12, for engagement with the lower bracket 2 carried by the supporting post 1. A second U-shaped band 15, having a roller 16 connecting the free ends of same and 95 adapted to bear against the down-turned ends of the upper horizontal pipe 3, is also provided with a ring 17 connected to the closed end of the U-shaped member 15 for engagement with the upper supporting 100 bracket 2, thus providing the hinged connection for my improved gate with the supporting post 1.

A pipe 18 formed with a closure 19 at the upper end of the same and also provided with external screw threads is positioned within the T-coupling 11 and adjustably supported therein by means of the lock nut 20. A wheel 21 positioned within the fork 22 has the shank 23 of the same extending 110

within the pipe 18, as is clearly indicated in Figure 4. In order to limit the vertical movement of the shank 18 and the wheel 21, the pipe 18 and shank 23 are connected together by means of the pin 24. The pipe 18 is provided on opposite sides with slots 25 to permit a partial rotary movement of the shank 23 and locking pin 24. The lower end of the pipe 18 is provided with screw threads 10 26 for supporting thereon the wheel guard 27. A coil spring 28 is positioned within the pipe 18, one end of said spring being in engagement with the closed end of the pipe, while the opposite end of said spring engages 15 the end of the shank 23 of the wheel fork 22, the purpose of which will be better understood as the description follows.

From the foregoing description of my invention, it can be readily seen that the U-shaped bands 12 and 15 provide hinge supports for my improved gate at one end, while the wheel 21 provides a support for the gate at the opposite end, and when the wheel is in the position shown in Figures 1 and 3, it 20 is impossible to open the gate, as the wheel 21 will act as a stop or wedge.

When it is desired to open the gate, the same as a whole is lifted upwardly, until the weight of the gate is removed from the 30 wheel 21, at which time the spring 28 in the pipe 18, forces the wheel 21 and shank 23 downwardly, and the locking pin 24 moving in the slots 25 gives a rotary movement to the wheel, thus forcing same to assume the 35 position indicated by dotted lines in Figure 2.

Prior to raising of the gate, pressure is exerted on the lever 29, which causes same to 40 swing on its pivot 30, thus moving the locking lever 31 and rod 32 outwardly against the tension of the spring 33, thus allowing the end of the locking pin 24 to pass beyond the locking lever 31, and upon release of the

lever 29, the spring 33 forces the locking lever back into position as indicated in Figures 1 and 3, thus preventing the weight of the gate from causing the wheel 21 to rotate back to normal position, as the lever 31 engages the pin 24 and holds the gate in a raised position, ready to be swung to either 50 side.

In view of the foregoing description of my invention taken in connection with the accompanying drawings, it is thought that any further explanation as to the construction, operation, and objects of same are unnecessary.

While I have shown and described the preferred form of my invention, I realize that various minor changes may be resorted to, without departing from the spirit and scope of the invention as claimed, and therefore, I do not wish to limit myself to the exact details of construction shown nor to the combination and arrangement of parts.

What I claim as new and desire to secure by Letters Patent is:

In a gate of the above described character, comprising a frame formed of tubular piping, means for hingedly supporting the gate at one end, a wheel adjustably mounted in the opposite end of said gate and adapted to support the free end of same, means positioned within one of the tubular pipes for rotating said adjustable supporting wheel 75 and means supported by one end of the gate for permitting said adjustable supporting wheel to assume a rotary and operative position for opening of said gate.

In testimony whereof, I have affixed my 80 signature in the presence of two witnesses.

GRANT NEWLAND.

Witnesses:

C. L. BURKE,
JOHN D. KELLEY.
